United States Patent

Des. 239,662
Patented Apr. 20, 1976

239,662

CURLING IRON

Leandro P. Rizzuto, Brooklyn, N.Y., assignor to
Continental Hair Products, Inc., Edison, N.J.

Filed Aug. 2, 1974, Ser. No. 494,676

Term of patent 14 years

Int. Cl. D28—03

U.S. Cl. D86—10 E

FIG. 1

FIG. 2

FIG. 1 is a perspective view of a curling iron in open position showing my new design;

FIG. 2 is a right side elevational view;

FIG. 3 is a top plan view;

FIG. 4 is a bottom plan view;

FIG. 5 is a front elevational view; and

FIG. 6 is a rear elevational view.

I claim:

The ornamental design for a curling iron, substantially as shown.
